UNITED STATES PATENT OFFICE.

EDWARD S. MASSIE AND JOHN HENRY HAWKINS, OF QUINCY, ILLINOIS.

CIRCUIT-CONTROLLER.

No. 858,197.

Specification of Letters Patent.

Patented June 25, 1907.

Application filed April 11, 1906. Serial No. 311,101.

To all whom it may concern:

Be it known that we, EDWARD S. MASSIE and JOHN HENRY HAWKINS, citizens of the United States, and residents of Quincy, in 5 the county of Adams and State of Illinois, have invented a new and Improved Circuit-Controller, of which the following is a specification.

Our invention is in nature a circuit closing 10 timer, or controller, employed in the sparkler circuit of explosive engines.

The object had in view is to provide means of the character stated, adapted for general circuit closing uses, but specially intended 15 for use in sparkler circuits as aforesaid.

The invention consists of the peculiar construction and arrangement of parts shown by the accompanying drawing, the novel features being pointed out in the appended 20 claims.

In the drawing, Figure 1 is a plan or front view of my invention, and Fig. 2 is a transverse vertical sectional view.

In the practice of our invention, we employ 25 any suitable and properly insulated case A, having its front closed by transparent material B, the same being secured on the case A, by a clamping plate C and set screws D, as will be understood. In the case are provided 30 cams E, arranged on the end of a shaft extended into the case indicated by dotted lines F. It will be understood that the shaft F is to have proper operative connection with working parts of the engine.

35 G denotes a screw threaded tube extending into the case A, as shown by Fig. 2. The inner end of the tube is constructed into a seat H, adapted for support of a circular body or ball I.

40 J, J' denote jam-nuts arranged on the outer end of the screw threaded tube G, the nut J being more in the form of a cap adapted to close the tube opening, and is constructed with an extended screw threaded shank K, 45 forming with the nuts L, suitable binding post for connection of the circuit wire M. It will be understood that circuit is completed through the engine parts as usual.

In the tube G, we arrange a spring N, and the same is placed under tension holding the ball I yieldingly seated, by adjustment of the nut J, as will be understood.

The construction of our invention will be understood from the above description. In its use, as the shaft F rotates the cams E will 55 contact the under portion of the ball I. During the contacting action, the ball is lifted from its seat H, see Fig. 2, and it is obvious that as the contacting cam E leaves the ball, the latter will be rotated to position, presenting a new contacting surface for engagement with the following cam, and it is further apparent, owing to the ball being free as to its rotary movement, that through frictional engagement of the cams therewith, its projecting surface, when seated, will be constantly changed, and thus insuring complete closure of the sparkler circuit, in timed arrangement, according to operative connection of the shaft F with moving parts of the engine.

We claim:

In a circuit controller and in combination, a casing, a rotatable shaft extending into the casing, a rigid circuit contact device in the casing, said contact device being arranged on the rotatable shaft adapted to be rotated thereby, a tube arranged extending into the casing, having inner and outer projecting ends, the tube being provided with screw-thread adjustment, an inner flange or seat on the inner end of said tube, a conductive ball device arranged in the tube to be seated on said flange and project beyond the tube, adapted to be engaged by the rigid rotatable contact device, adjusting nuts on the outer end of the tube, a spring holding the ball device yieldingly seated, and a binding post on the outer end of the adjustable tube.

EDWARD S. MASSIE.
JOHN HENRY HAWKINS.
